UNITED STATES PATENT OFFICE

DANIEL C. BOWMAN, WALTER A. RHODES, AND JAMES H. ESTES, OF LONG BEACH,
CALIFORNIA

BUILDING

Application filed July 25, 1929. Serial No. 380,973.

This invention relates to buildings, more particularly to a building of the tepee form, and has for its object to provide, in a manner as hereinafter set forth, a new, novel, strong, attractive, distinctive, sanitary and durable compartment building simulating a tepee and designed primarily for use as a dining room and kitchen, but it is to be understood that a building, in accordance with this invention may be employed for any purposes for which it may be found applicable.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

25 Figure 1 is a front elevation of a building in accordance with this invention and simulating a tepee.

Figure 2 is a vertical sectional view thereof. Figure 3 is a sectional plan of a building 30 in accordance with this invention.

Figure 4 is a side elevation of a unit or segment of the main framing.

Figure 5 is a sectional detail.

A building, in accordance with this invention, includes a main frame 1 of polygonal cross section and pyramidal contour. The building further includes a perpendicular, inner framing 2 of polygonal cross section and surrounded by and spaced from the lower portion of the main frame 1. The frame 1 extends over the top of frame 2 and is connected to the latter. The main frame 1 is anchored as at 3 to base members 4 preferably constructed of concrete.

45 The main frame 1 includes primary studdings 5 of the desired height and which are connected together in proximity to their upper ends by a coupling member 6 through which extend the upper portions of the primary studdings. Secured to the outer faces

of the primary studdings 5, at the lower portions of the latter are hip studdings 6' of a height materially less than the height of the primary studdings 5. The primary studdings 5 below the upper ends thereof are 55 formed with reinforcements 7 which are disposed lengthwise thereof.

The main frame 1 further includes upstanding auxiliary studdings 8 which are arranged between the primary studdings 5. 60 The studdings 8 are of different lengths and arranged equi-distance apart. The auxiliary studdings 8, as well as the primary studdings 5 and hip studdings 6' extend from base plate 9. Pairs of the auxiliary studdings 8 are 65 formed of spaced sections, the upper sections resting on cross members 10 and the lower sections extending to cross members 11. Arranged between the cross members 10 and 11 are brace members 12 which in connection 70 with the former provide openings in the lower portion of frame 1.

The primary studdings 5 are connected to the base members 4 by the coupling members 3. Brace members 13, 14, 15 and 16 are connected to the primary studdings 5 and to which the auxiliary studdings 8 are secured. The auxiliary studdings 8 extend towards the primary studdings 5.

Connected to the primary studdings 5 and 80 also to the brace members 13, 14, 15 and 16 are inclined truss members 17. Truss members 18 extend from the main frame 1 below and to the brace members 16. The lower ends of truss members 18 are arranged at the upper end of frame 2. Braces 19 are provided for truss members 18. A ceiling indicated at 20 is secured to the truss members 18. A wall forming means 21 is secured to the inner face of frame 1 above inner framing 2 85 and further secured to the inner face of the inner framing 2. The wall forming means 21 is provided with openings 22 which register with the openings 23 provided by the elements 10, 11 and 12. The inner framing 2 is 90 formed with openings 24 which register with openings 23. Boxings 25 are provided which extend from the openings 22 to the openings 24 and leading from the boxings 25 are drain pipes 26.

The main frame 1 is provided with a facing consisting of paper 27, wire mesh 28 positioned against the outer face of the paper, two coats of cement plaster 29, 30, the latter being positioned against the wire mesh 28. The cement plaster or coating 30 is of stucco finish and water proofed by paint or other suitable material. The wall forming means 21 consists of the same material employed as the facing for the main frame 1, but no stucco is employed, the wall forming means 21 having an interior plaster finish. The facing is arranged on the outer face of the framing 1 from the lower end of the latter to a point below the coupling means 6. The primary studdings simulate the poles of a tepee. The facing on the primary frame is to simulate the body of the tepee with the simulation of thrown back flaps 30'.
20 The boxing 27 connect the main frame 1 to the inner frame 2 and said frames have extending therethrough means, indicated at 31 to provide an entrance passage 32, formed at its inner end with a door 33. The inner frame 2 is not co-extensive with the inner face of the outer frame 1 and the ends of the inner frame 2 are indicated at 34.

Connected to the inner face of the outer frame, to the ends of the inner frame 2 and extending to the truss members 18 is a partition 35 which provides the interior of the structure, below the braces 16 with a dining room 36 and a kitchen 37. The partition 35 is formed with door openings 38 and doors 39 for closing such openings.

The partition 35 is also formed with serving windows 40. The partition 35 has secured to its front, centrally thereof shelving 41 and which is arranged between the serving windows 40.

Positioned within the dining room 36, centrally thereof and forwardly of partition 35 is a substantially U-shaped counter 42, surrounded by a U-shaped stool rest 43 provided with stools 43'. Arranged within the counter 42 and disposed centrally with respect thereto is a bar or counter 44. Secured to the inner framing 2 and extending towards the stool rest 43 are spaced tables 45. Arranged between certain pairs of the tables are pairs of benches 46. The benches of each pair are connected together by a common end 47 and the benches of each pair are oppositely arranged and further disposed at opposite inclinations with respect to each other. Single benches 48 are provided for certain of the tables 45 and each bench 48 has an enlarged outer end 49. The benches 46 and 48 are of greater length and height than the tables and are secured to the inner framing 2.

The dining room 36 is provided with a cashier's desk 49 attached to the inner framing and opposing a bench 50. Spaced from the desk 49 is a display stand 51, and between

the latter and the desk 49 is arranged a gate 52.

Within the kitchen 37 and extended through the outer framing 1 is an oven 53. A refrigerator 54 is arranged in kitchen 37 and a table 54'. An outlet for kitchen 37 is indicated at 55. Illuminating devices 56 are suspended from ceiling 21. The floor 57 of dining room 36 is formed of a suitable cement composition. The counter 42 opens at its rear and is spaced a substantial distance from the tables 45. The partition 35 and frame 1 have secured therewith suitable wall forming means for the kitchen 37.

What we claim is:

1. In building construction of the tepee type, an outer frame formed with spaced openings in proximity to its bottom and below its transverse median with transverse braces and inwardly extending, upwardly inclined trusses having their upper ends secured to said braces adjacent the ends of the latter, a polygonal shaped, perpendicular inner frame of less height than said outer frame and opposing in spaced relation the lower portion of the latter, said inner frame having spaced openings aligning with the openings in the outer frame, boxings open at each end, interposed between and secured to said frames and each registering with a pair of aligning openings, means secured to the inner face of the inner frame and to the inner face of the outer frame at a point between the top of the inner frame and the lower ends of the trusses to provide a wall, said means surrounding said openings in the inner frame, means secured to the lower faces of said trusses and braces to provide a ceiling extending from the top of said wall, a covering for said outer frame surrounding the openings in the latter, and a lining common to a boxing and the wall of that opening in the lower frame with which the boxing registers.

2. In building construction of the tepee type, an outer frame formed of primary and auxiliary studdings and spaced openings in proximity to its bottom, said primary studdings projecting above the auxiliary studdings, means for connecting the primary studdings together at a point in proximity to the upper ends thereof, said frame further including transverse braces and inwardly extending, upwardly inclined trusses having their upper ends secured to said braces adjacent the ends of the latter, said braces and trusses positioned below the transverse medium of said frames, a polygonal shaped, perpendicular inner frame of less height than said outer frame and opposing in spaced relation the lower portion of the latter, said inner frame having spaced openings aligning with the openings in the outer frame, boxings open at each end, interposed between and secured to said frames and each registering with a pair of aligning openings, means secured to

the inner face of the inner frame and to the inner face of the outer frame at a point between the top of the inner frame and lower ends of the trusses to provide a wall, said 5 means surrounding the openings in said inner frame, means secured to the lower faces of said trusses and braces to provide a ceiling extending from said wall, a covering for said outer frame surrounding the openings in the latter and extending from the bottom of the outer frame to the outer ends of the auxiliary studdings, and a lining common to a boxing and the wall of the opening in the lower frame with which the boxing registers.

10 15 3. In building construction of the tepee type, an inner and an outer frame, the former being of pyramidal contour and of materially greater height than the latter, the inner frame opposing the inner face of the lower portion 20 of the outer frame in spaced relation, means secured to the inner frame and a portion of the outer frame to provide the wall and ceiling of an enclosed space, said frames having aligning openings near the bottoms thereof, 25 a partition within and connected to the inner frame to provide a pair of communicating rooms, said wall and ceiling being common to said rooms, said means providing the walls surrounding the openings of the 30 inner frame, a covering for said outer frame surrounding the openings in the latter, and spaced boxings between and secured to said frames, each of said boxings being lined throughout and registering with a pair of 35 aligning openings.

40 4. In building construction of the tepee type, an outer frame tapering from its bottom to its top, a perpendicular inner frame of less height than the outer frame and 45 opposing the lower portion of the latter, wall forming means secured to the inner face of the inner frame and the inner face of the outer frame, said means terminating at its top at a point below the transverse median of the outer frame, ceiling forming means 50 secured to and within the outer frame below the transverse median of the latter and extending from the top of said wall forming means, said wall and ceiling forming means 55 providing an enclosed space below the transverse median of the outer frame, a facing of paper positioned against the outer face of the outer frame and extending from the bottom of the outer frame to a point below the top of the latter, foraminous means co-extensive with and positioned against the outer face of said paper, and a water-proof covering co-extensive with said foraminous means and adhering thereto.

60 60. In testimony whereof we affix our signatures hereto.

DANIEL C. BOWMAN.
WALTER A. RHODES.
JAMES H. ESTES.
